KEYLESS SWITCH

Filed Oct. 20, 1928

UNITED STATES PATENT OFFICE

ANDREW HIRT, OF NEW YORK, N. Y.

KEYLESS SWITCH

Application filed October 20, 1928. Serial No. 313,778.

This invention relates to keyless lock and in particular to a combination lock for use in connection with the dashboard of a motor vehicle so that the electric circuit of the machine may be broken and may only be completed by one having a proper knowledge of the operation of the circuit breaker.

A particular object of the invention is to provide a combination keyless switch upon which is mounted a number of combination dials, the dials themselves having circuit completing members which when properly manipulated complete a circuit through the switch so that operation of the vehicle can take place.

A still further object of the invention is to provide a combination keyless switch, parts of which may be rearranged without difficulty to change the combination. The switch is so constructed that in some of the dials there are buried current conducting rings whose ends extend to the peripheral edges of the dials, or rather the dial extensions within the switch, the projecting edges of the circuit completing members being arranged to co-operate or register with the ends of suitable members which form a circuit through the combination switch.

To enable others skilled in the art to fully comprehend the underlying features of my invention, that they may embody the same in the various modifications in structure and relation contemplated, drawings depicting a preferred form have been annexed as a part of this disclosure and in such drawings similar reference characters denote corresponding parts throughout all the views, of which,

Figure 1 is a fragmentary view of the dashboard of an automobile, illustrating the position thereon of my improved combination keyless switch,

Figure 2 is a face view of the combination switch constructed in accordance with my invention,

Figure 3 is a view similar to Figure 2, with the reverse side of the panel shown, the dial members carrying buttons some of which are arranged to carry circuit completing elements,

Figure 4 is an enlarged section taken on the

line 4—4 of Figure 2, and shows the construction of one of the dial members,

Figure 5 is an enlarged section taken through one of the guide bosses, showing the slot therein through the medium of which the cover is secured in place upon the panel, and,

Figure 6 is a view in perspective of the contact strip one end of which is arranged to be engaged by a suitable binding post while the other end is arranged to have sliding contact with ring extensions carried by the dial members.

Referring to the drawings in detail, 5 indicates a panel in which are revolvably mounted the dial members 6, suitable openings being provided as indicated by the numeral 7 in the face of the panel for the reception of the dial plugs 8 which are formed integrally with the dial members 6 and are arranged to receive the threaded end of the screws 9 each one of which is secured through the dial member to the dial button 10. This dial button is revolvably mounted, with the dial member, relatively to the panel 5, and it has embedded therein the contact ring 11 which is made of any suitable conducting metal such as for instance, copper, the ring being provided with the radial extension 12 which extends to the periphery of the dial button 10. In the formation of these dial buttons the ring 11 is of course moulded in the button so that only the outer end of the ring extensions are exposed. It is to be understood, of course, that the entire structure, that is the panel, the dial member and the dial buttons, are made of insulating material such for instance as bakelite, hard rubber or the like.

Arranged in suitable relation about the center of the panel 5 are the bushings 13, 90 which are moulded or pressed into said panel and arranged to receive the threaded end 14 of suitable binding posts 15. These binding posts are round as illustrated in Figure 3, although they may be of any suitable shape, 95 being provided with a suitable wire receiving opening 16 in which the conducting wire 17 is positioned, the same being held in place through the medium of the contact screw 18. These binding posts 15 are so arranged that 100

one will be adjacent to each of the dial buttons 10, it being understood that all of the working mechanism will be on the inner face 19 of the panel 5. The binding post 15 serves two purposes, that is it holds the end of the wire 17 in its upper portion and it secures the end 20 of a contact strip in position against the inner face 19 of the panel. This contact strip is made of a suitable conducting material and is provided with a piercing lip 21. This lip is punched out of the material of the center portion of the strip 22, and is arranged to engage the inner face of the panel to prevent sidewise movement of the strip. The free end of the strip is bent upon itself as at 23, so that its ring extension engaging end 24 will be at a higher level than the mid-portion. This difference is provided so that portion 24 will engage the extension of the contact ring 11 which is embedded in the periphery of the button 10. In referring to the wire 17, it will be noted that this numeral does not designate any particular wire but any or all of the wires that connect with the binding posts. It will be further noted with reference to Figure 3 that while the ring extension 12 for one of the outer dial members is relatively close together, the extensions 12 on the central dial member are diametrically opposite each other, this being necessary in order that a circuit may be completed across the dial as will be hereinafter described.

In order that working parts may be protected from dust or moisture, I provide a casing or cover 25. This casing is provided on its inner flanged surface with pegs 26, which are arranged to engage with slots 27 provided in the guide bosses 28 which are cast integral with and adjacent to the edge of the panel 5. These slots 27 are in the form of the well known bayonet slot, so that the cover or casing may be given a slight turn to lock the pins 36 in position in the bosses. As a further means of holding the casing in position upon the panel, use is made of set screws 29 which thread through the flanged side of the casing and engage the bosses 28.

It will be noted in Figures 2 and 4 that the dial members are provided with suitable dial markings, and while only one of the dials has been shown with these numbers or markings it is to be understood that all of the dials will be so marked, and a single indicating mark 30 will be employed adjacent to each dial into registry with which, any one of the numbers on the dial may be brought, to set the dial so that current will flow through the switch.

In referring to Figure 3 it will be noted that the lead-in wires 31 from the source of power are connected to the binding posts 32 and 33, from the latter of which extends a wire 17 which passes through a suitable opening 18 in the bosses 28, around the periphery

of the casing to another binding post 34 which in turn is connected through the medium of the wire 35 with one side of a key operated switch 36. The opposite wire 37 of the circuit, after it passes through lighting 70 and ignition systems, is brought back into the switch and connected to the binding posts 38. These binding posts 38 and 39 are connected through the medium of the wires 17' to the binding posts 15 and, as noted in Figure 3, 75 these binding posts secure one or more contact strips 22 in place so that their free ends rub against the periphery of the buttons 10, in some of which only the contact rings 11 are carried. Referring to Figure 2 it will be 80 noted in reading the same in connection with Figure 3 that the dials marked A, B and C are the only ones that have embedded therein the contact ring so that it is simply necessary for the operator of the car to remember the 85 three letter combination, in order that he may set the dials to the proper reading so that contact will be made between the free ends of the members 22 engaging the dials A, B or C. The other dials being blank may, of course, be manipulated at will without having any effect upon the circuit, and being all numbered alike it would be practically impossible for any one not knowing the combination to strike upon the right dials, and get 90 the right numbers, to complete a circuit.

The use of the key operated switch in connection with the wires 35 and 37 can of course be eliminated if desired, it having been illustrated simply for the purpose of showing 100 how it might be incorporated in the circuit as an extra precaution for use with the combination switch.

In the event that anybody should learn the combination, the owner may immediately 105 rearrange the same by removing the screw 9 and interchanging one of the dial members or buttons 10, so that it will be in different location and consequently the numbers for its operation will be different due to the angular position at which the extension 12 of the ring 11 will be disposed during the proper setting.

It is quite evident that in a construction of this character the parts may be made up so that they are interchangeable and may be made of a simplified nature so that the cost of producing the same is maintained at a minimum. It is also evident in a construction of this character that any combination may be arranged and any of the dials may be used to carry the circuit completing ring member. It will be noted that my combination lock switch, which is manipulated without the use of key, may be employed without 120 the key operated switch to break the ignition or operating circuit.

While I have illustrated and described my invention with some degree of particularity, I realize that in practice various alterations 125

therein may be made. I therefore reserve the right and privilege of changing the form of the details of construction, or otherwise altering the arrangement of the co-related parts without departing from the spirit of the invention or the scope of the appended claims.

Having thus described my invention, what I claim is new and desire to secure by United States Letters Patent, is:

- 10 1. In a keyless switch of the character described, a housing, a contact post, a contact ring having an extension thereon, a contact strip having one end thereof secured to the housing by the post, a piercing lip on the strip, and the end of the strip being bent out of the plane of the center portion thereof to engage said ring extension.
- 15 2. In a keyless switch of the character described, a housing, a contact post, a contact ring having an extension thereon, a contact strip having one end thereof secured to the housing by the post, and having a center portion, and a contact end, a piercing lip on the center portion, and the contacting end of the strip being bent out of the plane of the center portion thereof to engage said ring extension.

In testimony whereof I affix my signature.
ANDREW HIRT. [L. S.]
